(57) **CLAIM**

The ornamental design for an outdoor TV, as shown and described.

DESCRIPTION

FIG. 1 is a bottom, front, left side perspective view of an outdoor TV, showing my new design;

FIG. 2 is a top, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion of FIG. 1;

FIG. 10 is an enlarged view of a portion of FIG. 2;

FIG. 11 is an enlarged view of a portion of FIG. 4;

FIG. 12 is an enlarged view of a portion of FIG. 5; and,

FIG. 13 is an enlarged view of a portion of FIG. 7.

The evenly dashed broken lines are included to show features that form no part of the claimed design. The dot dash broken lines show the boundaries of the enlarged detail views and form no part of the claimed design.
